UNITED STATES PATENT OFFICE.

GEORGE HENRY WHEARY, OF RACINE, WISCONSIN.

CLOSET-FIXTURE.

1,195,156.

Specification of Letters Patent. Patented Aug. 15, 1916.

Application filed March 20, 1915. Serial No. 15,849.

To all whom it may concern:

Be it known that I, GEORGE HENRY WHEARY, a citizen of the United States, and resident of Racine, in the county of Racine 5 and State of Wisconsin, have invented new and useful Improvements in Closet-Fixtures, of which the following is a description, reference being had to the accompanying drawings, which are a part of this specification.

This invention relates to improvements in closet fixtures for holding garments.

In furnishing the closets of hotel rooms with garment hangers it has been found that 15 the hangers surreptitiously disappear and the hotel management would be under the expense of replenishing the supply from time to time.

It is one of the objects of the present invention to overcome the before mentioned objectionable features and provide a closet fixture adapted to have garment hangers mounted thereon which may be easily moved to drape garments thereon or remove them 25 therefrom without permitting the hangers being surreptitiously removed from the fixture.

A further object of the invention is to provide a closet fixture in the form of a 30 double track for holding garment hangers locked thereon and having means whereby the hangers may be easily removed by unlocking a portion of the fixture.

A further object of the invention is to 35 provide a closet fixture having extensible track ends which may be swung into alined positions to permit the hangers being separated to easily remove or replace garments thereon.

A further object of the invention is to 40 provide a closet fixture in which the means for locking the removable portions of the tracks also serves as a guard for preventing the surreptitious removal of the fixture from its support.

A further object of the invention is to 45 provide a closet fixture which is of simple construction, is strong and durable and is well adapted for the purpose described.

With the above and other objects in view 50 the invention consists of the improved closet fixture and its parts and combinations as set forth in the claims, and all equivalents thereof.

In the accompanying drawing in which 55 the same reference characters indicate the same parts in all of the views: Figure 1 is

a top view of the improved closet fixture shown mounted on a support, the extensible track member being indicated in closed position by dotted lines; Fig. 2 is a sectional view thereof taken on line 2-2 of Fig. 1; and Fig. 3 is an enlarged sectional detail view taken on line 3-3 of Fig. 2.

Referring to the drawing the numeral 5 indicates a support and 6 the improved 60 closet fixture mounted thereon. The fixture comprises the rear securing plate or bar 7 having forwardly projecting rods which form parallel tracks 8 upon which eyed garment hangers 9 are slidably mounted. The 65 tracks are round in cross section and have a threaded engagement 10 with the rear securing plate 7 as indicated in Fig. 3, and at their forward ends are provided with hinged extensions 11 which may be swung 75 horizontally from outer positions alined with the fixed tracks to inner positions extending toward each other and at right angles to the fixed tracks. The extension tracks are also round in cross section and the opposite end portions of the garment 80 hangers are provided with eyes or openings 12 through which the tracks extend. The outer ends of the extension tracks are provided with stop knobs or enlargements 13 85 which are of larger diameter than the openings 12 of the hangers so that the hangers cannot be removed from the tracks by pulling them off the forward ends of the rods.

The inner end portions of the fixed tracks 90 adjacent the securing plate 6 are recessed transversely to form slabbed or flat portions 14 into which extend the locking members 15 carried by the locking bar 16. These locking members 15 have bifurcated 95 lower portions which straddle the tracks with the portions 15' entering the transversely extending recesses and engaging the slabbed or flat portions thereof and thus prevent the tracks 8 from being surreptitiously unscrewed from the securing plate 100 and the hangers removed from the fixture.

The locking bar 16 is hinged at one end to the securing plate 6 by a pivot pin 17 and at its opposite end is provided with a depending tongue 18 which enters the lock 19 mounted on the securing plate 6 and locks the bar 16 in track engaging position. The lock 19 is controlled by a key 20. The securing plate 6 is connected to a support by 110 screws 21, a number of which are positioned in the rear of the locking bar 16 and cannot

be engaged unless the locking bar has been swung to open position.

In use the extensible tracks are swung into alignment with their respective fixed tracks 5 to provide sufficient space to separate the hangers and permit the removal of the garments therefrom. The extensible tracks also serve when in closed position to prevent the hangers working outwardly.

10 While the fixture has been described as a closet fixture and more particularly adapted for use in hotels, it is to be understood the fixture is also useful in private houses and other places than closets.

15 From the foregoing description it will be seen that the closet fixture is of simple construction and is well adapted for the purpose described.

What I claim as my invention is:

20 1. A closet fixture, comprising a securing member having means for connecting it to a support, a garment hanger track member removably connected to the securing member and projecting horizontally outwardly 25 therefrom and having a stop means on its outer end, means for preventing the surreptitious removal of the track member from the securing member, and garment hangers slidably mounted on the track 30 member.

25 2. A closet fixture, comprising a securing member having means for connecting it to a support, a garment hanger track member removably connected to the securing member 35 and projecting horizontally outwardly therefrom and having a stop means on its outer end, locking means for preventing the surreptitious removal of the track member from the securing member and the securing 40 member from its support, and garment hangers slidably mounted on the track member and locked thereto by the locking means.

3. A closet fixture, comprising a securing member having means for connecting it to a support, a garment hanger track member 45 revolvably connected to the securing member and projecting horizontally outwardly therefrom and having a stop means on its outer end, locking means for locking the track 50 member against rotation and for preventing the surreptitious removal of the securing member from its support, and garment hangers slidably mounted on the track member and locked thereto by the locking means.

55 4. A closet fixture, comprising a securing member having means for connecting it to a support, a horizontally extending garment hanger track member having a threaded engagement with the securing member and a stop means on its outer end, 60 said track member also having a flattened

portion adjacent its connection with the securing member, a locking member engaging the flattened portion of the track member to prevent its rotation, and garment hangers 65 slidably mounted on the track member and locked thereto by the locking member.

5. A closet fixture, comprising a securing member having means for connecting it to a support, spaced horizontally extending 70 track members having a threaded engagement at their inner ends with the securing member and provided with stop means at their outer ends, said track members having flattened side portions, a locking bar 75 mounted on the securing member and engaging the flattened portions of the track members to prevent the unthreading of said track members from said securing member, and garment hangers provided with openings 80 through which the track members extend, said openings being of less diameter than the width of the stop means of the track members, said hangers being locked on said track members by the lock bar.

6. A closet fixture, comprising a securing member having means for connecting it to a support, spaced track members having a threaded engagement at their inner ends with the securing member, said track members having flattened side portions adjacent their threaded ends, extension track members hinged to the outer ends of the threaded track members and arranged to swing from aligned positions with the threaded track 95 members to folded positions at right angles to the threaded track members, the outer ends of said extension track members provided with knobs or enlargements, garment hangers having openings in their opposite 100 end portions through which the track members extend, the openings of said hangers being of less diameter than the knobs of the extension track members, a locking bar pivotedly connected at one end to the securing members and having depending portions which engage the flattened portions of the threaded tracks to prevent the said tracks from being unscrewed from the securing member, and a lock for securing the free 110 end of the locking bar to the securing member when in closed position, the said locking bar also serving to prevent the removal of the securing member from its support when said locking bar is in closed position.

115 In testimony whereof, I affix my signature, in presence of two witnesses.

GEORGE HENRY WHEARY.
